DOUGHNUT MACHINE

Peter J. Toews, Minneapolis, Minn., assignor to
 Dough-King, Inc., Minneapolis, Minn., a corporation of Minnesota

Application May 1, 1939, Serial No. 271,003

9 Claims. (Cl. 53—7)

My invention relates to doughnut machines and particularly to doughnut machines in which the doughnuts are progressed along a way in the channel through the flow of the cooking liquid.

An object of the invention resides in providing a device adapted to be used at a bend in the channel for readjusting the doughnuts in the way to prevent jamming or sticking thereof and to dislodge doughnuts which may become stuck or jammed.

Another object of the invention resides in providing at the bend in the way shifting means normally disposed out of the path of travel of the doughnuts and adapted to be shifted laterally of the channel to readjust the positions of the doughnuts.

A still further object of the invention resides in constructing the shifting means as a curved plate adapted to be disposed adjacent a wall of the channel at the bend thereof when in normal position.

A feature of the invention resides in disposing said plate at the concave wall of the channel.

An object of the invention resides in constructing said plate reticulate.

Another object of the invention resides in providing a slide and guide means therefor and in attaching the plate to the slide.

A still further object of the invention resides in operating said shifting means periodically.

Another object of the invention resides in providing the machine with a control device for controlling the rate of travel of the doughnuts through the machine and in operating the shifting means in synchronism with the operation of the control device.

Other objects of the invention reside in the novel combination and arrangement of parts and in the details of construction hereinafter illustrated and/or described.

In the drawings:

Fig. 1 is a plan sectional view of a doughnut machine illustrating an embodiment of my invention.

Fig. 2 is a plan view of a portion of the structure shown in Fig. 1 and illustrating the parts in altered position, said view being drawn to a greater scale.

Fig. 3 is an elevational sectional view taken on line 3—3 of Fig. 2.

In the operation of doughnut machines in which the doughnuts are progressed along a way in a channel through the flow of the cooking liquid and where sharp bends are formed in the channel, the doughnuts frequently jam or stick and the force procured through the flow of the cooking liquid is insufficient to cause propulsion. This is particularly true where the movement of doughnuts is arrested by a control device oper-

ating to periodically control the rate of entry of doughnuts into a turner or ejector. The present invention provides a construction by means of which the doughnuts are dislodged and prevented from sticking and whereby positive travel of the doughnuts is procured.

In the drawings I have shown a doughnut machine A, which consists of a case 10 constructed with end walls 11 and 12 and side walls 13 and 14 connected therewith. The case includes uprights 15 disposed at the outer corners of the same which extend throughout the height of the case and to which the various walls are attached. Secured to the various uprights 15 are angle frame members, not shown, which stiffen the case and which serve as supports for the kettle of the invention.

Within the case 10 is disposed a cooking kettle 18 which is preferably of cast material and which is constructed with a bottom 19 and with vertical walls 21 extending upwardly therefrom. The vertical walls are connected together at their upper ends with upper walls 22 and the various walls are so arranged as to form a channel 23 which extends throughout the major portion of the kettle and which provides a way along which the doughnuts may travel. The kettle 18 has one corner of the same removed, as designated at 24, leaving a main portion 25 of the width of the case and of a length less than the length thereof. This construction also provides an extension 26 to the kettle which extends up to the end wall 12. The kettle 18 is constructed with a ledge 27 extending about the margin of the same which terminates in a lip 28 projecting upwardly from the extreme edge thereof. A guard 29, on the case 10, issues inwardly from the walls thereof and overlies the lip 28, thereby protecting the same and at the same time being spaced therefrom to retard transmission of heat from the kettle of the case. The kettle 18 is supported on the angle frame members attached to the uprights 15 in any suitable manner.

The channel 23 is arranged to provide a straight run 32 which commences in close proximity to the wall 12 and follows along wall 13. The channel 23, at the end of the run 32, makes a curve 33 which leads into another straight run 34 following along the wall 11. At the end of this run the channel has another curve 35 which leads into still another straight run 36 which follows along the wall 14. At the end of the run 36 the channel is constructed with a loop 38 which communicates with another loop or run 37. The latter run communicates with a straight run 38 which is parallel with the run 32. The run 38 discharges into a reservoir 39 which is merely an enlargement of said run. From this reservoir a short run 41 is provided which forms

part of a loop 40 connected to the beginning of the run 32.

The major portion 25 of the kettle 18 is enclosed by means of a hood 56. This hood utilizes the uprights 15 at the end wall 11 and two other uprights 57 which are attached to the case at the locality of the end of the major portion 25 of the kettle formed by the corner 24. Between these uprights are provided glass panels 58 which are slidably supported in guides 59 whereby the said panels may be removed. The entire hood is enclosed by a top, not shown, which is carried by the uprights 15 and 57. The hood is so designed that the same encloses the runs 33, 34, 15 35, 36 and 37 of the channel 23 and the major portions of the runs 38 and 32 leaving part of the reservoir 39 and the loop 40 disposed outwardly of said hood.

In the reservoir 39 is provided a vertical tubular duct 61 which communicates at its lower end with the bottom of the reservoir 39. In this duct is disposed a propeller or elevator 63 which is mounted on the armature shaft 64 of a motor 65. The duct 61 communicates at its upper end with the run 41 of channel 23, thus discharging the cooking liquid from the reservoir 39, and into the said run of the channel.

At the lowermost portion of the reservoir 39 is arranged a clean-out 71. This clean-out serves as a sump for collecting crumbs and other solid material formed in the operation of the machine. This construction forming no particular feature of the invention has not been illustrated in detail.

Situated at the beginning of run 32 of channel 23 is a doughnut former 72 which comprises a receptacle 73 for dough and a cutter 74 connected therewith. Such construction being well known in the art will not be described in detail in this application. The cutter 74 includes a flanged sleeve 75 which severs dough extrusions from the mass contained in the receptacle 73. This sleeve is reciprocated in opposite directions by means of a forked arm 76 which is mounted on a shaft 77. Shaft 77 is operated by a motor and transmission enclosed within a transmission housing 78. Inasmuch as the driving mechanism for the shaft 77 does not form a feature of the instant invention the same has not been illustrated. It will thus readily become apparent that doughnuts extruded from the doughnut former 74 are deposited in the flowing cooking liquid which travels along the run 32 of channel 23 in the direction of the arrow.

In the run 36 of channel 23 is arranged a twisted tubular turner 79. This turner inverts the doughnuts after the same have been cooked a predetermined length of time so that the said doughnuts may be cooked equally on both sides thereof.

The doughnut machine includes an ejector 81 which is disposed in the run 38 of channel 23. This ejector comprises a shaft 82 which is constantly driven from the transmission within the housing 78. This shaft has mounted on it oppositely extending cranks 83 and 84. Sets of toothed blades 85 and 86 are mounted on the said cranks and are adapted to be alternately raised and lowered as shaft 82 rotates. The lower ends of the blades slide upon a rest 87 which is mounted on the bottom 19 of receptacle 18 in the portion of the run 38 leading from the run 37. As the doughnuts reach the said blades the doughnuts are elevated and progressed upwardly and discharged outwardly of the cooking kettle 18.

The ejector 81 is disposed in a trough 88 having a discharge end 90 extending outwardly beyond the kettle. This trough returns the cooking liquid deposited upon the same back into the kettle.

For controlling the rate of travel of doughnuts along the channel 23, two controlling devices 91 and 92 are employed. These controlling devices operate to allow the doughnuts, one at a time, to enter the turner and ejector 81. These control devices are operated by a shaft 93 driven from the transmission within the housing 78 and are moved periodically at predetermined intervals. Inasmuch as any desired construction may be used for this purpose and since this construction does not form a particular feature of the instant invention, the details thereof have not been shown, nor will the same be described. Where the machine is of fairly large capacity the control devices 91 and 92 may be omitted and the rate of flow of the cooking liquid used to time the cooking of the 20 doughnuts.

For controlling the elevation of the cooking liquid in the channel, a dam 94 is employed which extends across the run 38 of channel 23, at the locality of the beginning of the reservoir 39. The cooking liquid, in flowing through the channel 23 passes over this dam and is maintained at a predetermined elevation thereby.

The invention proper consists of a shifting device which is constructed as a curved plate 101. 30 This plate is adapted to be positioned adjacent the curved wall 102 of the kettle 19 at the locality of the curve 42 thereof. This plate is reticulate, as shown in Fig. 3, being constructed with a number of holes 103 in the same. Plate 101 is attached to an arm 104 which extends upwardly above the upper wall 21 of the kettle 19 and is attached to a horizontally positioned slide 105. Slide 105 is preferably square throughout the major portion thereof, being formed with a rounded 40 end 108. This slide is guided at one end in a guide 106 attached to the ledge 25 of kettle 19 and at its other end in another guide 107 secured to the upper wall 22 of the kettle which later guide receives the round end 108 of said slide. The slide 105 is urged in a direction to move the plate 101 toward the wall 102 of the kettle by means of a tension coil spring 109. This coil spring is hooked at one end on a pin 111 secured to the guide 106 and at its other end to a pin 112, secured directly to said slide. 50

For operating the shifting device, shaft 93, which operates the control devices 91 and 92, is utilized. This shaft in the operation of the control device is periodically given a single rotation and then remains at rest until the next operation. This shaft, near the center of the same, is journalled for rotation in a bearing 113, secured to the upper wall 22 of the kettle 19. Adjacent this locality is provided a cam 114 attached to said shaft which is constructed with four lobes 115, best shown in Fig. 3. This cam is adapted to engage cam follower 116 secured to a reciprocating plunger 117. Plunger 117 is slidably mounted for reciprocation in a guide 118 secured to the upper wall 22 of the kettle. The end of the plunger 117, which I have indicated by the reference numeral 119, is adapted to engage an arm 121 of a lever 122. This lever is pivoted through a pin 123 to a bracket 124, issuing outwardly from the guide 118. The other arm 125, of lever 122, extends over the slide 105 and is pivoted thereto by means of a pin 126 which extends loosely through a hole in said arm and is secured to the said slide. This hole is of sufficient dimensions to accommodate 75

the oscillation of the lever 122 and to procure operation of the slide 105. Spring 109 normally holds the slide 105 in the position shown in Fig. 1, which moves the lever 122 in a clockwise direction 5 and urges the plunger 117 toward the cam 114.

The operation of the invention is as follows: When the doughnuts travel through the machine and are arrested by the control device 92, it frequently happens that the doughnuts become 10 lodged, one against the other, and when the control device releases the doughnuts the same do not move. As the control device is operated, cam 114 moves the plunger 117 in and out a number of times, depending upon the number of lobes 115. 15 This oscillates lever 122 and reciprocates slide 105. Reciprocation of slide 105 causes the plate 101 to move transversely of the channel and to jog the doughnuts adjacent the same loose, so that the doughnuts will continue to travel in the way 20 formed by the channel 23. In this manner the doughnuts are freed or dislodged and the machine continues to function without attention.

My invention is highly advantageous in that a doughnut machine of the type in which the 25 doughnuts are progressed by the flow of the cooking liquid is made positive in action so that uninterrupted performance of the machine occurs. By periodically operating the shifting device, positive dislodgment of the doughnuts is 30 procured. The invention may be embodied in existing doughnut machines without appreciable reconstruction or alteration thereof. My invention is extremely simple in construction and will not readily get out of order.

35 Changes in the specific form of my invention, as herein disclosed, may be made within the scope of what is claimed without departing from the spirit of my invention.

Having described my invention, what I claim as 40 new and desire to protect by Letters Patent is:

1. In a doughnut machine, a kettle providing a channel along which doughnuts are progressed by the flow of the cooking liquid, said channel having a bend therein and shifting means in 45 the channel at the bend and normally out of the path of travel of the doughnuts, and means for periodically moving said shifting means laterally of the channel to re-adjust the positions of the doughnuts in the channel.

50 2. In a doughnut machine, a kettle providing a channel along which doughnuts are progressed by the flow of the cooking liquid, said channel having a bend therein and shifting means in the channel situated at the concave side of the bend 55 and normally out of the path of travel of the doughnuts, and means for periodically moving said shifting means laterally of the channel to re-adjust the positions of the doughnuts in the channel.

60 3. In a doughnut machine, a kettle providing a channel along which doughnuts are progressed by the flow of the cooking liquid, said channel having a bend therein, a curved plate in the channel normally situated in close proximity to the concave wall of the channel at the bend and 65 normally out of the path of travel of the doughnuts, means for guiding said plate for movement transversely of the channel and means for periodically moving said plate laterally of the channel to re-adjust the positions of the doughnuts in the channel.

70 4. In a doughnut machine, a kettle providing a channel along which doughnuts are progressed

by the flow of the cooking liquid, said channel having a bend therein and shifting means in the channel at the bend and normally out of the path of travel of the doughnuts, said shifting means extending along the channel for a distance greater than the length of a doughnut, and means for periodically moving said shifting means laterally of the channel to re-adjust the positions of the doughnuts in the channel.

5 5. In a doughnut machine, a kettle providing 10 a channel along which doughnuts are progressed by the flow of the cooking liquid, said channel having a bend therein, means for controlling the rate of travel of the doughnuts in the channel, shifting means in the channel at the bend and 15 normally out of the path of travel of the doughnuts, means for operating said control means and means operated in synchronism with said last named means for moving the shifting means laterally of the channel to re-adjust the positions of the doughnuts in the channel.

6. In a doughnut machine, a kettle providing 20 a channel along which doughnuts are progressed by the flow of the cooking liquid, said channel having a bend therein, means for controlling the 25 rate of travel of the doughnuts in the channel, shifting means in the channel at the bend and normally out of the path of travel of the doughnuts, means for operating said control means and means operated by the last named means 30 for moving the shifting means laterally of the channel to re-adjust the positions of the doughnuts in the channel.

7. In a doughnut machine, a kettle providing 35 a channel along which doughnuts are progressed by the flow of the cooking liquid, said channel having a bend therein, a reticulate plate in the channel normally situated in close proximity to the concave wall of the channel at the bend and 40 normally out of the path of travel of the doughnuts, means for guiding the plate for movement transversely of the channel and means for periodically moving said plate laterally of the channel to re-adjust the positions of the doughnuts 45 in the channel.

8. In a doughnut machine, a kettle providing 50 a channel along which doughnuts are progressed by the flow of the cooking liquid, said channel having a bend therein and being formed with a vertical wall on the concave side thereof, a vertically extending curved plate in the channel normally situated in close proximity to the denoted 55 wall of the channel at the bend and normally out of the path of travel of the doughnuts, means for guiding said plate for movement transversely of the channel and means for periodically moving said plate laterally of the channel to re-adjust the positions of the doughnuts in the channel.

9. In a doughnut machine, a kettle providing 60 a channel along which doughnuts are progressed by the flow of the cooking liquid, said channel having a bend therein and being formed with a vertical wall on the concave side thereof, a vertically extending curved plate in the channel normally situated in close proximity to the denoted 65 wall of the channel at the bend and normally out of the path of travel of the doughnuts, a slide guided for movement transversely of the channel, an arm attached to said plate and guide, and means for periodically moving said slide in its 70 guides to shift said plate laterally of the channel.
